UNITED STATES PATENT OFFICE.

ROBERT E. REARDON, OF OTTAWA, ONTARIO, CANADA.

EXPLOSIVE TARGET.

1,321,849.

Specification of Letters Patent. Patented Nov. 18, 1919.

Application filed March 13, 1917, Serial No. 154,563. Renewed February 25, 1919. Serial No. 279,178.

To all whom it may concern:

Be it known that I, ROBERT EDWIN REARDON, a subject of the King of Great Britain, residing in the city of Ottawa, in the Province of Ontario, Dominion of Canada, have invented a new and useful Improvement in Explosive Targets, of which the following is a specification.

This invention relates to targets which will indicate by audible means when a bull's eye hit is made. The object of the invention is to devise a target that will indicate such shots in a way that will create and hold popular interest in shooting at such a target and yet will be very cheap to make. Another object of the invention is to provide a target for use with what is known as target practice rods wherein an extensible rod is applied to a gun adapting it for miniature target practice without the use of explosives. The desired end is attained by substituting for the explosion in the gun, an explosion on the target when a perfect shot is made.

With the objects in view, the invention consists in the construction, combination and arrangement of parts hereinafter described and particularly pointed out in the claims, it being understood that I do not intend to limit myself to the details of construction of the various parts.

The invention is illustrated in the accompanying drawings in which—

Figure 1 shows a front elevation of one form of this invention.

Fig. 2 shows a front elevation of another form.

Fig. 3 shows a front elevation of the device of Fig. 2 with the pivoted front cover turned down.

Fig. 4 shows a vertical central sectional view of the device of Fig. 2.

Fig. 5 shows a paper disk forming a part of the device of Fig. 2.

Fig. 6 shows a front elevation of still another form of this invention.

Fig. 7 shows a vertical sectional view of the device of Fig. 6.

Fig. 8 shows a front elevation of a carrier or holder for any or all of the devices of Figs. 1 to 7.

Fig. 9 shows a modified detail.

In the drawings, the numeral 11 indicates a block formed of any suitable material forming a carrier for the target proper and its operating mechanism. This block houses in its upper part, a spool 12, removably jour-

naled on a pin 13. This spool carries a strip of paper or tape 14 wound upon it, which tape has provided upon it a plurality of targets having bull's eyes 15 and 15. 60 These bull's eyes are either composed of or carry explosive disks or caps. The tape 14 passes from the roll through a slot 17 in the front face of the carrier 11 down over the front face to the bottom of the carrier where 65 it passes through another slot 18. Under the front face at the bottom of the carrier, is provided a resilient roller 19 operated manually by means of a knurled head 20, which roller frictionally engages the tape 70 14 so that operation thereof moves the tape downwardly, unwinds it from the spool and re-positions new targets. 21 represents mechanisms for limiting rotation of the roller 19 to one direction. An edge 23 is provided 75 whereby the used targets may be torn from the strip of good ones. 24 indicates means for hanging up the carrier 11.

In the modified form shown in Figs. 2 to 5, 11^a represents a carrier corresponding to 80 the carrier 11 in Fig. 1. This carrier is provided with a front face 25, pivoted at 26, so that it may be turned down, as shown in Fig. 3. The front face 25 carries a target 27 of the type used for bull's eyes 28 and 29 85 thereon, one that is aimed at and the other which is actually hit. This target is movably held by any suitable means such as grooves or the bar 30. Back of the front face, the carrier 11^a has journaled in it, a 90 metal disk 31, carrying a square pin 32 and having, near its periphery, a series of apertures 33, which are larger on the back of the plate than on the front. 34 represents a spring back of the plate acting upon it to 95 cause its rotation. 35 indicates a finger carried by the plate, adapted to engage a stopping pin 36 on the carrier. Means for permitting the plate to rotate step by step are provided in a plunger 37, having a round 100 head for engagement with the apertures 33. This plunger is acted upon by a spring 38, carried in the back of the carrier 11^a. 39 indicates a paper disk carrying a series of explosive caps 40, positioned to register with 105 the apertures 33 when the disk 39 is applied to the plate 31, as indicated in Fig. 4. The square opening 41, in the paper disk, fits upon the square pin 32 of the plate 31 to cause this registering without any difficulty 110 in Figs. 6 and 7, 11^b indicates a carrier equivalent to the carriers 11, and 11^a, previously

described. The upper part houses a spool 43, removably journaled on a pin 44 and adapted to carry a tape 45, having a plurality of explosive disks or caps 46 placed 5 along its center line. 47 indicates perforations carried by the tape 45. The tape passes from the spool downwardly through a passageway, extending longitudinally of the carrier 11^b and just in front of its rear 10 face. 49 indicates a plunger or firing pin extending from the front face of the carrier inwardly to set off or fire the caps 46 as they pass behind it. Movement inwardly of this pin 49 moves the arm 51 rigidly attached 15 thereto at 50, which arm engages the teeth on 52 and rotates roller 53 step by step. This roller carries pins 54 adapted to engage perforations 47 of the tape, so that it is moved a step at a time whereby a new cap 20 is fed to exploding position behind the pin 49 as soon as the previous one has been fired. The carrier 11^b is adapted to receive a paper target 55 in all respects similar to the target 25 27 in Fig. 2. The target will be so placed that the bull's eye actually hit will be placed immediately over the firing pin 49.

As the target should be approximately in the plane of the shooter's eye, it will be understood that its height must be changed to 30 suit different individuals and to render this easy, a device is provided that is shown in Fig. 8. It consists of a back 65 of any suitable material but preferably light metal having its lateral edges 66 curved around upon 35 themselves, which edges are adapted to engage any of the devices of Figs. 1, 2 and 3 by the provision of grooves 67 in their sides for the edges 66 to engage. 68 represents means for suspending the holder upon the 40 wall. The edges 66 frictionally engage the grooves 67 of the carriers so that they may be readily adjusted vertically to the desired height.

In Fig. 9, a slight modification is shown in 45 which, instead of placing the explosive caps on the paper targets, a projection 60 is provided on the bull's eye to be hit on the usual paper target 61 and the explosive cap 62 is placed in a holder 63, carried by the target 50 practice rod 64 of the gun.

The operation of the invention is as follows: In Fig. 1, the target is shot at and if a bull's eye hit is made, the cap or disk located at or forming the bull's eye is exploded so the shooter knows of the perfect 55

shot. Upon the explosion of a disk, the shooter turns the head 20 which causes the unwinding of the spool carrying the tape formed of targets and brings a new one into shooting position.

In Figs. 2 to 5, if the shooter hits the bull's eye, a cap is exploded in the same manner. However, the impact causing the explosion of the cap will cause the momentary retraction of the spring pressed plunger 37, which 60 retraction from the aperture in the plate 31 that it engaged will permit the spring 34 to rotate the plate 31 and paper disk 39. The plunger 37 will return to normal position at once because of the spring 38 and will engage the next aperture 33 as it comes around and thereby stop the plate 31 and paper disk 39 with a new explosive cap in bull's eye position ready for another shot from the gun. This automatic action continues until 65 all the caps have been exploded. Then the shooter must put a new paper disk upon the plate 31 and give the plate one rotation to 70 rewind the spring 34 when the device is ready for use again.

In the device of Figs. 6 and 7, the impact of a bull's eye hit depresses the plunger or firing pin 49 and the cap behind it is exploded. Movement of the pin 49 is transmitted through its associated mechanism to 75 rotate the roller 53 one step which in turn removes the exploded cap from behind the plunger 49 and replaces it with a new one by movement of the tape 45 carrying the caps a step at a time. This feed is automatic 80 90 until all the tape on the spool 43 has been used whereupon it must be replaced with new by the shooter.

What I claim is:

1. A flexible target having an explosive 95 bull's-eye integral therewith.
2. A target composed of flexible fibrous material having an explosive bull's-eye integral therewith.
3. A target comprising a sheet of flexible 100 material having a plurality of spaced explosive caps constituting bull's-eye.
4. A device of the class described, including a target, two bull's-eyes, so located relative to each other that when one is in the line of sight the other is in the line of fire and explosive means carried by the bull's-eye in the line of fire.

R. E. REARDON.
